ATTORNEY

UNITED STATES PATENT OFFICE

HARRY C. CLAYBURGH, OF OAKLAND, CALIFORNIA, ASSIGNOR TO DAWSON MANUFACTURING COMPANY, OF OAKLAND, CALIFORNIA

CAN HOLDER

Application filed November 11, 1929. Serial No. 406,349.

The invention forming the subject matter of this application relates to semi-automatic lifting device, and has particular reference to a device for lifting a number of cans from a conveyor belt in order to more easily and conveniently handle said cans in commercial manufacturing operations.

Another object of my invention is to provide a device which will hasten the operation of packing the finished cans in shipping boxes by increasing the number of cans handled at one time and by providing a feature whereby the correct number of cans to form one layer in a packing box are selected each time the can-lifter is operated.

A still further purpose of my invention is to provide a lifter of the nature set forth which will be superior in points of simplicity, inexpensiveness of construction, 20 positiveness of operation, facility and convenience of use, and in general efficiency.

In this specification and the annexed drawings, the invention is illustrated in the form considered to be best, but it is to be understood that the invention is not limited to such form, because it may be embodied in other forms, and it is also to be understood that in and by the claims following the description it is desired to cover the invention 30 in whatsoever form it may be embodied.

These above objects have been accomplished by means of such structure and relative arrangement of parts as will be more particularly described with reference to the 35 accompanying drawings of said invention in which:

Fig. 1 is a side elevation of the can lifting device with a portion of the said machine in section;

Fig. 2 is a top plan view of the invention; Fig. 3 shows an end elevation of the can lifter in the closed position.

Referring to the accompanying drawings 45 wherein similar reference characters designate similar parts throughout, the various figures described above adequately illustrate my invention and the following detailed description is commensurate with the above 50 mentioned drawings in enabling an artisan

to construct and assemble the constituent parts of the same.

The mechanism of the can lifting device consists of a stationary length of strap-iron 1 upon which certain projections 2 are provided at definite and regular intervals to engage the rims of the cans to be handled. To the two ends of the stationary length of strap-iron are firmly fastened lighter strap-iron plates 3 bent into the shape of a quadrant of a circle, and having a portion of the piece bent in such a manner as to permit its being attached rigidly to the stationary piece 1. The function of this curved plate 3 is to guide the cans into position so that they may be grasped securely by the device when operating rapidly.

To the middle of and at right angles to the stationary piece 1 is attached a lighter piece of strap-iron 4, the latter being bent to form a hand-rest 5 and to provide a stationary pivot 6 for the moving strap-iron holding bar 7. The strap-iron holding bar 7 has upon its inner surface certain projections corresponding to and coinciding exactly with the projections 2 on the stationary bar 1. In order that the holding bar 7 may be moved outward when it is desired to engage the cans and pressed inwardly to hold the cans securely while transferring them from conveyor to packing box, the holding bar is attached to the strap-iron lever bar 8 which has a pivoted fulcrum at 6 and an extension handle 9.

When it is desired to lift a load of cans, 55 the extension handle 9 is moved downward with relation to the hand-rest 5, thus causing the holding bar 7 to be moved outward by virtue of the action of the lever bar 8 to which the holding bar 7 is attached. When 60 in this opened position the device is placed over the cans to be lifted, the curved quadrant plates 3 guiding the cans into their respective positions with reference to the projections 2 which are to hold the cans in place. 65 When this has been accomplished, the extension handle 9 is pressed into or toward the hand-rest by the hand of the operator, thus causing the holding bar 7 to force the cans against the stationary bar 1. This action 70

of exerting a compressive force upon the ends of the cans in conjunction with the projections 2 which fit under the rims of the cans, holds them in position and allows them to be transferred as a unit from the conveyor belt to the packing box and therein deposited.

Although I have shown and described a preferred embodiment of my invention, it is to be understood that changes within the domain of mere form, construction, or arrangement may be made by persons skilled in the art without involving any change in mode of operation, function, or of result described in the appended claims.

What I claim is:

1. A device for lifting a plurality of adjacent cans disposed in parallel relation to each other, comprising a pair of cooperating members hingedly related to each other and adapted to engage the opposite ends of said cans, a plurality of projections extending at regularly spaced intervals from the inner surface of each of said members so as to engage the can rim at the opposite ends of each can, means for guiding a definite number of said cans into operative position with respect to said projections, and means for operating said members to engage and disengage said cans.

2. A device for lifting a plurality of adjacent cans disposed in parallel relation to each other comprising a pair of parallelly disposed cooperating members hingedly related to each other and adapted to engage the opposite ends of said cans, a plurality of projections extending at regularly spaced intervals from the inner surface of each of said members so as to engage the can rims at the opposite ends of each can, guide members positioned adjacent the opposite ends of one of said parallel members for guiding a definite number of said cans into operative position with respect to said projections, and a pair of levers connected to said parallel members for operating said members to engage and disengage said cans.

3. A can lifting device comprising a pair of parallel lifter bars provided each with a plurality of inward projections equally spaced and adapted to engage the top and bottom rims of a plurality of cans when horizontally disposed, one of said bars having centering guides at the ends thereof adapted to cooperate with the sides of cans, said bars having affixed thereto transversely related hingedly connected cooperating levers forming a carrying handle, and adapted to cause said bars to close when said levers are gripped.

4. A can lifting device comprising a pair of lifter bars provided with a plurality of equally spaced inward projections adapted to engage the top and bottom rims of a plurality of cans, one of said bars having at

each end an arcuately formed gauge adapted to center a plurality of cans by cooperation with the outermost cans, said bars being hingedly related by means of a pair of transversely related coating levers adapted to cause closing of said bars when said levers are closed, said levers constituting a carrying handle.

5. In combination with a can lifting device adapted to lift cans by means cooperating with the rims of said cans; means cooperating with the sides of said cans for centering said rim cooperating means relative to said cans.

6. In combination with a can lifting device adapted to lift a plurality of cans in parallel relation by cooperation of spaced engaging members with the rims thereof; a pair of oppositely disposed periphery engaging members adapted to center said device in rim engaging relation when superposed on said plurality of cans.

In testimony whereof I have affixed my signature.

HARRY C. CLAYBURGH.
